LEVER OPERATED GUN WITH VERTICALLY
SLIDABLE BREECH BLOCK

William B. Morris, Fort Worth, Tex.

Application May 15, 1950, Serial No. 161,930

8 Claims. (Cl. 42—24)

1

This invention relates to firearms having magazines for carrying cartridges, and has reference to rifles having lever operated cartridge loading, cocking and case extracting mechanisms. Certain features of the invention are not limited to lever operated rifles, but may be used in various types of rifles and guns.

An object of the invention is to provide a lever operated rifle capable of firing ammunition having higher pressures than present repeating lever rifles.

Another object of the invention is to provide a rifle of the referred to class having a shorter over all length, where the barrel and stock are of standard lengths, for more convenient handling.

Another object of the invention is to provide a lever operated rifle or gun construction whereby the action, particularly the rearward movement of the carrier, does not interfere with the preferred butt stock construction and shape.

Another object and feature has to do with improvements in a dropping (vertical action) breech block mechanism, not necessarily limited to lever operated rifles, whereby high pressure cartridges may be fired with greater accuracy, and yet provide for extraction of the expanded cases.

A particular object of the invention is to provide a novel turn bolt construction and arrangement for coaction between a dropping breech block and an operating lever, whereby the advantages of a lever operated gun may be used in accomplishing the foregoing objects.

Another object of the invention is to provide a dropping breech block which may be shorter than the length of the cartridge for carrying out the preceding object.

A further object of the invention is to provide a turn bolt construction as referred to and so located as to accommodate a magazine in the gun frame.

A further object of the invention is to provide an extractor adapted to support the rim of a "rimless," semi-rimmed, or rimmed type cartridge head, and which extractor is also supported to resist the lateral forces of the explosion within the cartridge. The portion of the cartridge rim not engaged by the extractor is also engaged and supported by the chamber of the barrel.

A further object is to provide a trigger mechanism entirely carried by the lever and whereby the mounting thereof is less difficult and less expensive as compared with trigger mechanisms mounted in the frame.

2

A further object of the invention is to provide a safety mechanism in which the trigger sear is moved to increase its surface area in contact with the gun sear when the safety mechanism is "off," as compared with the contacting area between said sears when the gun is ready to fire.

A still further object of the invention is to provide a safety mechanism and arrangement whereby the gun sear is locked when the lever is partially opened or extended.

The invention will be more readily understood by reference to the accompanying drawings and following description.

Figure 1 is a broken elevation and sectional view of a rifle action embodying the features of the present invention.

Figure 2 is a broken elevation and sectional view of the magazine of the rifle illustrated in Figure 1.

Figure 3 is a transverse sectional view taken on lines 3—3 of Figure 2, but showing the breech block removed.

Figure 4 is a broken perspective of the rifle illustrated in Figure 1, and showing the action in its open position.

Figure 5 is a plan view of the turning bolt and breech block.

Figure 6 is a sectional view taken on lines 6—6 of Figure 5.

Figure 7 is a broken elevation of the rear end of the breech block, viewed from the opposite side from that shown in Figure 1, and showing the relative position of the cocking piece when the breech block is in its lowermost position.

Figure 8 is an enlarged perspective view of the cartridge carrier and showing the same attached to the lever arm, and additionally showing the barrel breech in broken section and in its relative position with respect to the extractor.

Figure 9 is a broken perspective view of the forward end of the carrier and showing its engagement with the rim of the cartridge head.

Figure 10 is a plan view of the cartridge carrier and showing the same ejecting a fired case.

Figure 11 is an end view of the barrel breech and slot therein to accommodate the extractor.

Figure 12 is a front perspective view of the breech block and cartridge carrier.

Figure 13 is a broken sectional view of the trigger and safety mechanism and showing their relation to the gun sear.

Figure 14 is a sectional view taken on lines 14—14 of Figure 13.

The rifle illustrated in Figure 1 includes a barrel 16, a frame 17, and a stock 18, together with

a receiver 19 mounted above said frame. The barrel 16 is threadedly engaged in the forward end of the receiver 19, and the stock 18 is secured to the rear end of the frame by means of a stock bolt 21. The receiver 19 is secured to the frame 17 by means of screws 22 in the manner illustrated in Figures 1 and 4. Within the rearwardly projecting tang 23 of the frame 17 there is a linking arm 24 having an elongated slot 25 in one end through which a pin 26 passes, and which pin is secured to the sides of the frame 17. A crescent shaped spacer 27 is slidably disposed within the slot 25 and bears against the pin 26 by reason of a compression spring 28 positioned between said spacer and the end of said slot. The end of the linking arm 24 opposite the pin 26 is slotted to receive a projection 29 integral with the operating lever 30. Pivotal connection between the linking arm 24 and the lever projection 29 is provided by means of a screw 31. The lever 30 extends downwardly and through an opening 32 in the lower portion of the frame 17, and includes a handle 33 having a hand opening 34. Forwardly of the handle 33 there is a trigger guard 35, and the upper end of the lever 30 is provided with an integral forwardly projecting lever arm 36. The forward end of the lever arm 36 is received within a cavity 37 in a cartridge carrier 38 and is pivotally secured thereto by means of a pin 39. The sides of the carrier 38 are provided with longitudinal tongues 40 which slidably engage longitudinal grooves 41 in opposite sides of the receiver 19. As shown in Figure 8, the tongues 40 are cut away intermediate their ends so as to accommodate the lever arm attaching pin 39. As shown in Figure 1, the forward end of the lever arm 36 is provided with a cam 42 for bearing against a thrust pin 43 slidably mounted and forwardly directed in front of the carrier 38. As will become apparent, the action of the cam 42 on the pin 43 has to do with initially dislodging the cartridge 44 from the cartridge chamber 45. The last described action is carried out by means of a claw type extractor 46, as shown in detail in Figures 1 and 8. It will be noted that the inner surface 47 of the extractor 46, between the forward end of the carrier 38 and the inwardly projecting claw 48 bears against the rim 49 of the cartridge head 50. The outer surface of the extractor 46 is in sliding contact with the surface of a cavity 51 in the breech of the barrel 16. As shown in Figures 8, 9 and 12, the extractor 46 is arcuate as viewed from the forward end and comprises substantially 90 degrees. It will also be noted that the inner point of the claw 48 does not necessarily contact the groove 52 of the cartridge head 50. The cartridge rim 49 is completely chambered and in contact with the barrel chamber 45 except where it is in contact with the supported extractor 46; thus, the rim 49 is completely supported against the expanding pressures of the explosion within the cartridge 44.

Within one side of the frame 17 and substantially parallel with the axis of the barrel 16 there is a turn bolt assembly 53 illustrated in Figures 4, 5, and 6. The turn bolt assembly 53 includes a tubular sleeve 54 including an enlarged forward end 55. Another or forward tubular sleeve 56 is slidably received within the enlarged end 55 of the first referred to sleeve, and there is a relatively strong compression spring 57 within said enlarged end for urging the first described sleeve 54 rearwardly. A longitudinal slot 58 in the enlarged sleeve end 55 accommo-

dates a lateral projection 59 integral with the last described sleeve 56, and which projection includes an extending arm 60 having a round hand bar 61 integral with its outer end. It will be noted that the last described bar 61 is parallel with the sleeve 56, and that the said sleeve and arm 60 comprise means for raising and lowering a substantially vertically operating breech block 62, to be described. As shown in Figure 6, the slot 58 is wider than the projection 59 is thick, and whereby a delayed operating action is accomplished when raising and lowering the breech block 62. The sleeves 54 and 56 are pivotally mounted on a pin 63 supported in opposing transverse walls 64 of the frame 17. Near the rearward end of the rearward sleeve 54 there is a laterally projecting lug 65 adapted to engage an opening 66 in the lever 30. During operation of the lever 30, it is apparent that the opening 66 will completely disengage the projection 65, but by reason of the spring 57 and the frictional engagement of the ends of the sleeves 54 and 56 on the frame walls 64, the projection 65 will remain in position for re-engaging the opening 66. The surface of the lever 30 opposite the projection 65 is relieved, as at 67, to accommodate the referred to re-engagement.

The breech block 62 includes a rectangular body 68 having a vertical recess 69 in its lower surface arranged to accommodate the arm 60 of the hand assembly. Opposing recesses 70, formed in the sides of the first recess 69, slidably and rotatably receive the lifting bar 61 for raising and lowering the breech block 62. The forward end of the breech block 62 has substantially vertical projections 71 on each side which slidably operate in corresponding grooves 72 in the forward end of the receiver 19. The breech block body 68 is longitudinally drilled and reamed to accommodate a striker 73 which includes a secured flange 74 near its forward end, and a pin 75 integral with said striker normally projects outwardly from the forward end of the breech block 62. The rear end of the breech block body 68 is provided with a drilled closure 76 which slidably accommodates the striker 73. A main spring 77 is coiled about the striker 73, bears against the striker flange 74, and against the closure 76, which is secured in place. A cocking piece 78 is secured to the rearward end of the striker 73 and projects downwardly where it is provided with a guide 79 which is slidably received within the rearward end of the breech block 62. A lateral projection 80 integral with the upper end of the cocking piece 78 is arranged to engage the rear surface of an arcuate flange 81 integral with the enlarged portion 55 of the turn bolt sleeve 54. When the turn bolt projection 65 is raised, a cam 82 on the surface of the sleeve 54 contacts a projection 83 integral with the receiver 19, and compresses the turn bolt spring 57 and moves the flange 81 forwardly.

Referring now to Figures 1, 4 and 7, there is an L-shaped gun sear 84 pivotally mounted on a vertical bracket 85 supported by the frame 17. The forward leg 86 of the sear 84 is provided with a laterally projecting lug 87 arranged for coaction with an opposingly arranged lug 88 integral with the lower end of the cocking piece 78. The upper and lower edges of both lugs 87 and 88 are beveled in opposite directions, and as will become apparent, and have to do with quickly releasing the cocking piece 78. A pin 89 mounted on the bracket 85 limits the forward movement of the lower leg 90 of the gun sear 84. A hairpin

spring 94 mounted on the bracket 85 urges the lower sear leg 90 toward the last described pin 89.

The trigger mechanism is comprised of a trigger 92 pivotally mounted by means of a pin 92a through the lever 30 and extends downwardly therefrom into the trigger guard 35 near the rear end of the latter. The forward end of the trigger 92 includes a trigger sear 93 arranged for contacting the lower rear surface of the gun sear leg 90, as shown in detail in Figure 13. Above the trigger sear 93, and integral with the lever 30, there is a downwardly and forwardly projecting triangular lug 94 which is received in an arcuate groove 95 in the side of the lower sear leg 90 when the gun is fired. Beneath the last referred to groove 95, and on the same side of the sear leg 90, there is a recess 96 which will permit the lever 30 to be operated. However, a projection 97 between the groove 95 and the recess 96 will lock the sear 84 to prevent accidental discharge of the gun in the event that the lever 30 is not completely closed.

The lower edge of the trigger 92 forward of the pin 92a is recessed to accommodate a trigger spring 98. An adjustment screw 99 is threaded through the trigger 92 to engage the upper end of said spring, and a lock nut 100 is provided on said screw for maintaining the desired adjustment. A safety 101 in the form of a lever having flanged edges 102 is positioned around the forward portion of the trigger guard 35 and is pivotally mounted on its upper end of the said guard by a pin 103 passing therethrough. The upper end of the safety 101 has a rearwardly directed projection 104 against which the trigger spring 98 presses. Above the pin 103, and integral with the safety 101, there is an upwardly directed projection 105 having a round forward corner 106 for engaging and lifting a lug 107 depending from the trigger sear 93. Beneath the trigger sear 93 and secured to the lug 107 there is a leaf spring 107a which will allow upward movement of said trigger sear when the safety is moved rearwardly and whereby the end area of said trigger sear against the leg 90 of the gun sear is increased when the safety is "on."

As shown in Figures 2 and 3, the present description includes a magazine 108 which is substantially U-shaped in cross section and is curved to fit the contour of the frame 17. The magazine 108 includes end plates 109 which fit between the previously described frame walls 64. A pin 110 through the frame walls 64 and the end plates 109, and positioned within the lower end of the magazine 108, provides hinged operation for opening and closing the magazine. As particularly shown in Figure 3, the upper ends of the magazine 108 are shaped so that they permit cartridges 44 to be moved upwardly by a magazine spring 111, and subsequently loaded in the barrel chamber 45. A conventional latch 112 may be provided for locking the magazine in its closed position, the details of which are not shown.

The side of the receiver 19 opposite the magazine 108 is provided with an elongated ejection port 113 whereby the firing cases 114 may be ejected. The last referred to operation is carried out by means of an L-shaped ejector lug 115 having one end thereof mounted in the receiver 19 and having the remaining end forwardly directed towards the head of the fired case 114, and toward the side of the latter adjacent the upper end of the magazine 108.

In the following description of operation, it will be assumed that the cartridge 44 in the

barrel chamber 45 is ready to be fired and that the action is cocked, as shown in Figure 1. Pulling the trigger 92 moves the trigger sear 93 downwardly, releasing the gun sear 84 and the cocking piece 18. The action of the main spring 11 causes the firing pin 15 to strike and fire the cartridge 44.

The initial operation of the lever 30 moves the turn bolt projection 68 downwardly and the sleeve projection 82 falls off of the cam 83 integral with the receiver 19. The length of the slot 66 in the lever 30 is such that it allows the sleeve projection 68 to be moved rearwardly by the turn bolt spring 51. The turn bolt flange 81 contacts the projection 80 on the cocking piece 18, and since the turn bolt spring 51 is stronger than the main spring 11, the firing pin 15 is drawn into the breech block 62. Further operation of the lever 30 causes a small projection 116 on the under forward end of the lever arm 36 to contact the upper surface of the breech block body 63 and to break the breech block 62 from the head of the fired case 114. Immediately thereafter, and by reason of continued operation of the lever 30, the hand bar 61 begins to move the breech block 62 downwardly, and at the same time the cocking piece lug 88 moves downwardly in front of the gun sear lug 87. The continued operation of the turn bolt spring 51 continues to move the cocking piece 18 rearwardly and when the breech block 62 is in its lowermost position, the upper rear corner of the cocking sear lug 88 is positioned beneath and rearwardly of the forward lower corner of the gun sear lug 87. Since the top side of the breech block 62 is positioned below the head of the fired case 114, the cam 42 on the forward end of the lever arm 36 contacts the thrust pin 43 and initially moves the carrier 38 rearwardly and initially breaks the case 114 from the barrel chamber 45.

Continued operation of the lever 30 moves the carrier 38 rearwardly, and causes the head of the fired case 114 to engage the ejector lug 115, and by reason of the relative position of the latter, the case is thrown outwardly through the port 113 in the receiver 19. During the case ejecting operation, a depending cartridge pickup 117 integral with the forward end of the carrier 38 and on the side thereof adjacent the magazine 108 moves rearwardly along the uppermost cartridge 44 in the magazine. After the pickup 117 is positioned rearwardly of the cartridges 44, the action of the spring 111 in the magazine 108 moves the uppermost cartridge 44 to a position whereby the pickup 117 may engage the head of the same. The forward movement of the carrier 38 is carried out by the closing operation of the lever 30. Upon leaving the magazine 108, the nose of the cartridge 44 contacts the inner surface of the receiver 19, and the continued forward movement of the carrier 38 positions the cartridge nose in the barrel chamber 45. The pickup 117 contacts the end of the head of the cartridge 44 during the last described operation, and when the cartridge becomes aligned with the axis of the barrel 16, a depending projection 117a contacts the end of said cartridge head for completing the loading operation. As shown in Figure 12, there is a longitudinal slot 117b in the upper surface of the breech block 62 to accommodate the last described projection 117a. Thus initially aligned, the continued movement of the carrier 38 completely chambers the cartridge 44.

When the lever 30 is fully extended, as shown in Figure 4, the lever slot 66 is disengaged from

the turn bolt projection 65, but the latter is maintained in its downwardly position by reason of the frictional engagement of the ends of the turn bolt sleeves 54 and 56 against the frame walls 64. As the lever 30 is closed, the slot 66 re-engages the turn bolt projection 65 and causes the hand rod 61 to raise the breech block 62. At this time the opposing beveled surfaces on the lugs 88 and 87 of the cocking piece 78 and gun sear 84, respectively, engage each other and additionally move said cocking piece rearwardly. At this time the trigger sear 93 engages the depending leg 90 of the gun sear 84. Just before the lever 30 is completely closed, the sleeve projection 82 engages the cam 83, causing the turn bolt flange 81 to move forwardly. When the lever 30 is completely closed the triangular lug 94 on the said lever is positioned to clear the projection 97 on the gun sear leg 90. The action is now cocked and ready to fire.

If desired, the safety lever 101 may be pivoted rearwardly causing its upper projection 105 to engage the projection 106 on the trigger 92. The last described operation not only locks the trigger mechanism but has the additional effect of raising the trigger sear 93 whereby the area of its end surface is increased where it contacts the surface of the gun sear leg 90. To release the safety mechanism the safety lever 101 is moved forwardly and the action of the spring 107a beneath the trigger sear 93 moves the latter downwardly although it remains in contact with the sear leg 90 until the trigger 92 is manually operated.

As shown in Figures 1, 3 and 12, an ejection port cover may be provided in the form of an elongated plate 118 which is substantially in the form of an inverted U in its rearward cross section and having a forwardly directed side whereby the same may be attached, such as by screws 119 to one side of the breech block body 68. As the breech block is lowered and raised the ejection port is opened and closed. It is to be understood that the plate 118 is shaped to avoid contact with the described parts contained within the receiver 19.

The present invention is not limited to the specific construction herein shown and described, but may be made in many ways within the scope of the appended claims.

What is claimed is:

1. In a gun action including a breech block near the barrel breech, a rotatable turn bolt parallel with and disposed laterally in spaced relationship from the axis of said barrel breech, and at least one projection on said turn bolt arranged for coaction with said breech block.

2. In a gun action including a dropping breech block adjacent the barrel breech, a rotatable turn bolt parallel with and disposed laterally in spaced relationship from the axis of said barrel breech, and a projection on said turn bolt connected with and constructed and arranged for raising and lowering said breech block.

3. In a gun action, the combination of a breech block having means in the forward end thereof for locking the same adjacent a barrel breech, a rotatable turn bolt parallel with and disposed laterally in spaced relationship from the axis of said barrel breech, a projection on said turn bolt, and means connecting said projection with said breech block for raising and lowering the latter.

4. In a gun action including a dropping breech

block adjacent the barrel breech, and including a spring loaded firing pin normally projecting forwardly from said breech block, a rotatable turn bolt parallel with and disposed laterally in spaced relationship from the axis of said barrel breech, a projection on said turn bolt connected with said breech block and constructed and arranged for raising and lowering the latter, and cam means carried by said turn bolt for retracting said firing pin.

5. In an extractor for removing a fired case from a barrel chamber, a shank having a claw integral with its forward end and arranged to engage the rim of said case to be extracted, the inner surface of said shank being in contact with the rim of the fired case and means supporting the outer surface of said shank being in contact with the rim of the fired case and means supporting the outer surface of said shank.

20 6. In a gun action, a dropping breech block adjacent the barrel breech, a turn bolt parallel with and disposed laterally in spaced relationship from the axis of said barrel breech, a projection extending from said turn bolt and arranged for connection with said breech block for raising and lowering the latter, a second projection extending from said turn bolt, a lever mounted in said gun action, and including an opening therein arranged for engaging the last said projection.

7. In a gun action, the combination of a breech block adapted to close the barrel breech, a rotatable turn bolt parallel with and disposed laterally in spaced relationship from the axis of said barrel breech, and a projection on said turn bolt constructed and arranged for locking said breech block in its described position relative to said barrel breech.

8. In a gun action, the combination of a dropping breech block including a firing pin, striker and cocking piece assembly and having means in the forward end thereof for locking the same adjacent a barrel breech, a rotatable turn bolt parallel with the axis of said barrel breech and disposed laterally in spaced relationship from said axis and from said breech block, a lever mounted in said gun action, means carried by said turn bolt and engaging said breech block for raising and lowering the latter on rotation of said turn bolt, means carried by said turn bolt cooperating with the cocking piece of said assembly for retracting said firing pin on rotation of said turn bolt, and means carried by said turn bolt adapted to engage said lever for rotation of said turn bolt responsive to the action of said lever.

WILLIAM B. MORRIS.
